INVENTOR.

Sarah M. Mourer.
BY
Niedusheim & Landau,
ATTORNEYS

UNITED STATES PATENT OFFICE.

SARAH MERTIE MOURER, OF PHILADELPHIA, PENNSYLVANIA.

TOY VEHICLE.

Application filed July 6, 1926. Serial No. 120,666.

This invention, generally stated, relates to toys and has more especial relation to a toy vehicle for use by children which is propelled by the foot action of the person using 5 the toy.

The leading object of the present invention may be said to provide a simple, efficient and comparatively inexpensive toy of the character stated which in addition to furnishing amusement to a child affords the child sufficient exercise to promote exhilaration in the open air the advantages of which are readily apparent.

A further object of the present invention 15 is to provide an arrangement, connection and combination of parts for attaining the results sought by the leading object.

Further and other objects of the invention will appear hereinafter.

20 The invention consists of the novel construction hereinafter described and finally claimed.

The nature, characteristic features and scope of the invention will be more fully understood from the following description taken in connection with the accompanying drawings forming part hereof, and in which:

Fig. 1 is a view in side elevation partly sectioned illustrating a toy embodying features of the invention.

Fig. 2 is a top or plan view thereof.

Figs. 3 and 4 are respectively fragmentary views in elevation of the ratchet devices shown in Fig. 2.

35 Fig. 5 is a view in transverse section taken upon the line 5—5 of Fig. 1; and

Fig. 6 is a view in transverse section taken upon the line 6—6 of Fig. 1.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings in detail and with especial reference to Figs. 1 and 2, the reference numeral 1 designates the body or supporting frame of the toy, and is provided 55 at its rear with an axle 2 provided with trac-

tion wheels 3. The forward portion of the frame 1 is provided with an axle 4 provided with knuckle joints 5 connected with steering wheel 6 the steering of said wheel 6 being effected by a steering wheel 7 the entire 60 structure being very similar to that of an automobile. To the rear of the axle 4 are a pair of short shafts 8 suitably supported and each provided with a friction cone 9, which friction cones are operatively connected with a drum 10 so that during retrograde movement of one friction cone 9 the drum is being moved in the direction of the arrow in Fig. 1 by the other friction cone 9. The drum 10 is provided with a sprocket wheel 11 and connecting this sprocket wheel 11 and a sprocket wheel 12 on shaft 2 is a sprocket chain 13 so that as the pair of shafts 8 are rotated by mechanism about to be described, positive movement of rear axle 2 is maintained in 70 the direction of the arrow shown in Fig. 1 to propel the toy in a forward direction. Intermediate the laterally extended shafts 8 and the rear axle 2 is arranged a rock shaft 14, it being understood that the shafts 8, 80 rock shaft 14, and axle 2 are all rotatably supported by the frame 1. Fixed to the rock shaft 14 at each side of the casing 1 is a bell crank lever 15, each of which bell crank levers 15 are provided with a foot rest 16. 85 The opposite end of each bell crank lever 15 has its forward portion notched to provide teeth 17 the extreme lower end of each bell crank lever 15 being provided with a counterweight 18. Each section of shaft 8 has fixed thereto a member 19 having opposed notched or toothed portions 20 and opposed plain surfaces 21. In order to maintain the bell crank levers 15 in cooperative relation with respect to the members 19 use is made 90 of coiled springs 22 which are interposed between a bell crank lever and a support 23 fixed to the bottom of housing or casing 1.

In use a child stands upon the foot pedals 16 and grasps the steering wheel 7. As the child alternately depresses the foot pedals 16 the teeth of the bell crank levers 15 cooperatively engage the teeth 20 of the members 19 to propel forward the vehicle by means of the sprocket chain 13. In the connection it will be observed that while the foot work of the operator produces an alternate movement of the shafts 8 a continuous movement of the rear axle is obtained. Thus, after depression of a foot pedal 16 105

the teeth 17 of a bell crank lever ride over the plain surface 21 of a member 19 so that no positive driving action is had. Obviously, however, during the travel of said teeth over said plain surface the other foot pedal is being operated to mesh with the teeth of the opposite member 19 to propel the vehicle forward.

Having thus described my invention, what I claim as new and desire to secure by Letters Patent, is:—

1. In a device of the character stated, a body provided with a rear axle having a sprocket wheel and including a pair of traction wheels, a pair of forward wheels including a steering wheel for said body, a cross-shaft having a pair of mutilated toothed wheels and a sprocket wheel, a sprocket chain connecting said sprocket wheels, a rock shaft and a pair of spring pressed bell-crank levers upon said rock shaft one end of each lever having a foot pedal and the opposite end of each lever being toothed for engagement with a toothed wheel, whereby the operator may stand upon

said pedals and maintain his balance by grasping said steering wheel.

2. In a device of the character stated, a body substantially symbolic of an automobile provided with a rear axle having a central sprocket wheel and including a pair of traction wheels, a pair of forward wheels including a central steering wheel for and projected above said body, a forward cross-shaft having a pair of toothed wheels and a sprocket wheel arranged intermediate said toothed wheels, a sprocket chain connecting said sprocket wheels, a rock shaft arranged intermediate said sprocket wheels, and a pair of bell-crank levers upon said rock shaft, said levers being arranged upon opposite sides of said sprocket chain and one end of each lever having a horizontal foot pedal, and the opposite end of each lever being toothed for engagement with a toothed wheel, whereby the operator may stand upon said horizontal pedals and maintain his balance by grasping said steering wheel.

SARAH MERTIE MOURER.
